UNITED STATES PATENT OFFICE.

ANDREW ROADS HUNSAKER, OF FULTON, KENTUCKY.

DRAFT-DETACHING DEVICE.

SPECIFICATION forming part of Letters Patent No. 380,628, dated April 3, 1883.

Application filed January 31, 1888. Serial No. 262,549. (No model.)

To all whom it may concern:

Be it known that I, ANDREW ROADS HUNSAKER, a citizen of the United States, residing at Fulton, in the county of Fulton and State of Kentucky, have invented a new and useful Improvement in Detaching Devices for Plows and Vehicles, of which the following is a specification.

The invention relates to improvements in detaching devices for plows and vehicles; and it consists in the construction and novel combination of parts hereinafter described, illustrated in the drawings, and pointed out in the claims hereto appended.

15 In the accompanying drawings, Figure 1 represents a perspective view of the front part of a plow-beam having the detaching device, which is a clevis, attached. Fig. 2 represents a vertical longitudinal section of the same. Fig. 3 represents a side view of the invention having a modification of the spring. Fig. 4 is a partial vertical section of the modification shown in Fig. 3.

25 Referring to the drawings by letter, A designates the front portion of a plow-beam, having the detaching-clevis B secured to its end. The said clevis consists of the plate-bar C, secured to the under surface of the plow-beam by the bolts c c', and the angular bar D, connected to the outer end thereof a suitable distance in front of the end of the plow-beam by the hinge-joint d. The bolt c extends through and above the said beam and through an opening, e, in the rearwardly-extending arm E of the bar D, near the end of said arm.

35 f is an opening from front to rear in the bolt c above the arm E, and F is a split spring-key engaged in said opening to keep the bar E locked on the bolt c, and having its legs extending frontward and its loop rearward.

40 G is a cord having its front end secured to said loop and its rear end tied or otherwise loosely attached to some part of the plow-frame—such as one of the handles—within easy reach of the driver. By means of this cord the driver can readily draw the key and allow the clevis to open, thus releasing the draft bar or tree.

45 H is a coiled spring seated in a recess, h, in the upper side of the plow-beam around the shank of the bolt c', and bearing upward against the bar D to throw the same off the plow-beam when the key is drawn.

In Fig. 4 a leaf-spring secured to the upper surface of the plow-beam is shown as a substitute for the said coiled spring. The tapped ends of the bolts c c' are respectively engaged by the nuts c² c³, seated in their proper recesses in the upper surface of the plow-beam, as shown in Figs. 2 and 4, and the tapped end 60 of the bolt c' passes through an opening, c⁴, in the bar E, so that the latter can descend fully to the beam against the spring.

The device can be used with a single or double tree by securing two of them transversely 65 near the ends thereof.

The mode of operation of the invention is clearly evident from the foregoing description.

Having described my invention, I claim—

1. The combination, with the beam, of the 70 plate-bar, the bolts inserted through said bar and the beam, the angle-bar hinged to plate-bar and fitting over the ends of the bolts, the detachable securing means for the angle-bar, and the spring for forcing the angle-bar away 75 from the beam on the release of the securing means, as set forth.

2. The combination of the plate-bar, the angle-bar hinged to the front end thereof and provided with an opening in the end of its 80 rearwardly-extending arm, the bolt connecting the plate-bar and the angle-bar and having a perforation in its extension above the angle-bar, a key engaging said perforation, the spring bearing upward against the rearwardly- 85 extending arm of the angle-bar, and the cord extending from said key to a point within easy reach of the driver, substantially as specified.

3. The combination, with the beam provided with the recess h, the bolt c', the perforated bolt c, the nuts on said bolts, and the coiled spring H, seated in the recess h, of the plate-bar C, the angle-bar D, provided with the openings d' and c⁴ and connected to the 95 plate-bar by the hinge d, the split spring F, and the cord G, all constructed and arranged substantially as shown and described, for the purpose specified.

In testimony that I claim the foregoing as my 100 own I have hereto affixed my signature in presence of two witnesses.

ANDREW ROADS HUNSAKER.
